EAR PROTECTING DEVICE

Max Sahlmann, New York, N. Y., assignor to
Losala, Inc., New York County, N. Y., a cor-
poration of New York

Application May 22, 1942, Serial No. 444,030

3 Claims. (Cl. 2—209)

This invention relates to an ear covering device, such as an ear muff, for protecting the ear against thermal, acoustical and/or other disturbances. In particular, the invention refers to a device for protecting the ear against cold, or to apply to the ear an acoustical device such as a telephone, and to protect it at the same time against undesired outside noises and possibly cold.

Heretofore, ear muffs were applied to the ear and held in position by means of straps connecting a pair of muffs applied to both ears. The same way, earphones were applied to the ear by means of springy metal straps. Hats or helmets were also provided with flaps to cover the ears against cold or to apply earphones to them.

It is an object of the invention to simplify the means by which covering or protecting devices of this type are applied to the ear or ears.

It is another object of the invention to construct ear covering or protecting devices of the type concerned in such a manner that they can be individually and independently applied to each ear.

It is a further object of the invention to construct ear covering or protecting devices, particularly ear muffs, in such a manner that they cover the ear as completely as possible and are held firmly in their position on the ear.

It is still a further object of the invention to render the manufacture of ear covering or protecting devices inexpensive and their application to and removal from the ear simple.

These and other objects of the invention will be more clearly understood when the specification proceeds with reference to the drawings in which Fig. 1 shows a front view of the covering or protecting device applied to an ear, in this exemplification of the invention to the left ear, Fig. 2 a cross sectional view along line 2—2 in Fig. 1, Fig. 3 a back view of the covering or protecting device, Fig. 4 a cross sectional view along line 4—4 in Fig. 3, Fig. 5 a cross sectional view along line 5—5 in Fig. 3, Fig. 6 certain elements of the device seen from its inside, Fig. 7 a cross sectional view similar to that of Fig. 2 of a modification of the invention for applying an earphone, Fig. 8 a cross sectional view of the device similar to that of Fig. 4 with its elements in another relative position, Fig. 9 a view of an element to be used for the purpose of the invention, and Fig. 10 the same element when bent to the shape in which it is finally applied.

The device according to the invention as ex-

emplified in the drawings consists substantially of an outer cover 10, Figs. 1, 2, 4, 5, 7 and 8, of flexible material, preferably textile or fabric, provided with a lining 11, Figs. 2 to 5, 7 and 8, of similar material on the inside.

A stiff but somewhat elastic C-shaped member or blank 12, Fig. 9, is e. g. cut or stamped from suitable, somewhat elastic sheet material, such as thin and preferably light weight sheet metal, or fibrous board material, e. g. cardboard or glazed paper, or plastic sheet material, such as known under the trade name "lucite," and bent by connecting its preferably spaced end portions 13, 14 by suitable means, such as a rivet or eyelet 15, Fig. 10, leaving free an opening 16. Thereby the blank 12 is somewhat deformed and made concave or convex, as the case may be, and in any event interior elastic stresses are caused therein tending to keep the member either in its concave or convex shape.

As to be seen particularly from Figs. 3 to 5, member 12 so bent and stressed in its concave shape is covered by a piece 16 of felt, textile, fabric or like material the outer configuration of which conforms substantially to that of bent member 12, and which is cut at the inside to form flaps 17 which are folded around edge 16 of member 12 and pasted or in any other suitable way fastened to the latter, as to be seen particularly on Fig. 6.

An overlapping strip 19 is folded over the outer edges of covers 10 and 16 and fastened to the covers, the member 12 and lining 11 by a sewn seam 20.

The bent member 12 in one of the two of its rest positions will be concave, as shown in Figs. 3 to 5, and convex in the other one, as shown in Fig. 8, and when it is pressed from either position just beyond a plane which can be laid through its outer edge, it will snap into the opposite rest position.

When member 12 with cover 16 occupies the concave rest position shown in Figs. 4, 5, any number of such devices can be stacked in a pile and easily shipped. When member 12 with cover 16 occupies its convex outwardly bent position shown in Fig. 8; it is apparent that considerable space is offered inside the device between member 12 and lining 11 so that it can easily be slipped over an ear 21 into a position shown in Fig. 1 and, in dotted lines, in Fig. 2. By pressing the device from the outside against the head, member 12 will be pressed from its convex position inside, thereby pass a plane laid through its outer edge and tend to snap into its concave

position; being prevented by the ear 21 to reach that concave rest position, member 12 by the elastic stresses caused therein will be pressed resiliently against the ear in the position as shown in full lines in Fig. 2.

It will be appreciated that in the position of the device shown in full lines in Fig. 2, the cover 16 with its opening 21 closes tightly in upon the ear which is now substantially covered on the outside by cover 10 and lining 11 whereby an effective protection of the ear against thermal and, if desired, acoustical disturbances from the outside is attained. It is not necessary, however, to press the device always against the head into a position as shown in Fig. 2 in full lines; satisfactory protection is also afforded in many cases when the device is left in its position and shape as shown in dotted lines on Fig. 2.

It will further be appreciated that the device due to its structure and particularly the bent member 12, is firmly held on the ear without resorting to straps reaching over the head which cause discomfort to the wearer and are expensive if of metal. It can be easily slipped over and removed from an ear. Any desired number of individual elements 10, 11, 12 or 16 can be cut or stamped simultaneously from a pile of proper sheet material, assembled and sewn together. Thus the manufacture of the device according to the invention is simple and inexpensive in mass production.

If it is desired to convey to the ear acoustical waves or sounds, such as caused by a telephone, the feature according to Fig. 7 can be used to advantage. There an electro-magnetic telephone 22 is fastened to the inside of cover 10, 11 for instance by means of seam 23, and insulated electric wires 24 are introduced through a hollow projection 26 of telephone 22 which snugly passes a hole 25 in cover 10, 11. In this case also the device may either be applied to and left on the ear in the convex shape of member 16 as indicated in dotted lines in Fig. 7, or in a stressed position of that member as shown in full lines. The cover of fabric protects the ear against disturbing noises and, if it be cold, also against the latter. The sounds generated by telephone 22 are directly conveyed to the ear and there essentially undisturbed reception secured by the device.

It will be appreciated that the covering or protecting device according to the invention can be applied individually to each ear, and closely and firmly adheres to it. The device encloses the ear as fully and tightly as desired, and requires the least possible space for storing and shipping.

It should be understood that the invention is not limited to any particular feature and material as hereinbefore described by way of ex-

emplification only, and is to be derived in its broadcast aspects from the appended claims.

What I claim is:

1. An ear covering or protecting device, substantially comprising a full portion larger than the ear and to form an outer cover thereof, said full portion of flexible material as exemplified by fabric and felt, another portion provided with an opening through which the ear can be slipped, said other portion tightly attached to said full portion near its circumference and substantially consisting of fibrous material as exemplified by fabric and felt, and a flat and substantially elastic, C-shaped member associated with said other portion, and leaving free its opening, the adjacent ends of said member connected so as to reduce their distance and bend said member, thereby rendering it capable of transverse snap action.

2. An ear covering or protecting device, substantially comprising a full portion larger than the ear and to form an outer cover thereof, said full portion substantially consisting of fibrous material as exemplified by fabric and felt, another portion tightly connected with said full portion near its circumference and provided with an opening through which the ear can be slipped, said other portion of fibrous material as exemplified by fabric and felt, and a C-shaped member of elastic sheet material, as exemplified by a thin metal sheet, card-board or plastic sheet material, the ends of said member connected so as to reduce their distance and deform it and cause in it elastic stresses, said member associated with said other portion so that said member and other portion are capable of occupying two positions, one being concave and the other one convex, and if pressed from one of said positions beyond a plane laid through the outer circumference of said member tend to occupy said other position by transverse snap action.

3. An ear covering or protecting device, substantially comprising a full portion larger than the ear and to form an outer cover thereof, said full portion of flexible material as exemplified by fabric and felt, another portion provided with an opening through which the ear can be slipped, said other portion tightly attached to said full portion near its circumference and substantially consisting of fibrous material as exemplified by fabric and felt, and a flat and substantially elastic, C-shaped member associated with said other portion and leaving free its opening, the adjacent ends of said member made to overlap one another and connected so as to deform it and cause in it elastic stresses rendering it capable of transverse snap action.

MAX SAHLMANN.
